UNITED STATES PATENT OFFICE.

LAROY S. STARRETT, OF ATHOL, MASSACHUSETTS, ASSIGNOR TO THE L. S. STARRETT COMPANY, OF ATHOL, MASSACHUSETTS, A CORPORATION OF MASSACHUSETTS.

HACKSAW-MACHINE.

1,245,815.

Specification of Letters Patent.

Patented Nov. 6, 1917.

Application filed February 5, 1916. Serial No. 76,457.

To all whom it may concern:

Be it known that I, LAROY S. STARRETT, a citizen of the United States, residing at Athol, county of Worcester, Commonwealth 5 of Massachusetts, have invented certain new and useful Improvements in Hacksaw-Machines, of which the following is a specification.

This invention relates to the control or 10 feed of hack saw machines of the gravity type and particularly to such control of the machines shown and described (but not claimed), and to the combination of the control with the machine.

15 In such gravity fed sawing machines, there is a destructive tendency which seriously lessens the otherwise great advantages of the gravity feed. This tendency results in broken saw blades, mutilated work, and 20 damage to the machine by shock, and even involves risk to the operator of the machine.

25 It is the object of my present invention to provide means for overcoming this tendency in saw machines in general and in particular to embody the invention in a combination with a machine in which there is a peculiar need and in which it has a combined and modified effect.

30 The embodiment of my invention in practical form is shown in the accompanying drawings in combination with the machine (not claimed) with which it most effectively combines. It should be understood, however, that while especially adapted for use 35 in a machine of the type shown, my invention may be used in any hack-saw machine in which the frame is adapted to be lifted from the work. In brief, my invention consists in "floating" a gravity fed saw frame 40 which normally has no lifting effect during its reciprocations on a by-passed oil cylinder, and in providing a mechanical lift effective for a free upraising of the saw, though controlled in reverse direction by the 45 check cylinder.

45 Heretofore, when placing new work in the machine, the saw frame has usually been raised by hand. This is objectionable, both because of the extreme weight of the frame 50 and its mechanism, and because it required the use of the hands at the very time when needed for inserting and adjusting the new work in the work clamp. By my construction, the operator is relieved of this manual lift, and the saw frame is raised by the

weight of the operator exerted upon a treadle connected to the frame. This leaves the operator's hands free, as well as enabling the saw frame to be more easily raised. The saw frame is supported in its position by 60 the oil piston, thus allowing the operator to give his full attention to the manipulation of the work.

Throughout specification and drawings, like reference numerals indicate corresponding parts, and in the drawing,

Figure 1, is an elevation of one side of a machine equipped with my invention.

Fig. 2, is an elevation of the machine from the opposite side, with the saw raised. 70

Fig. 3, is a detail of the saw supporting construction as applied to the machine shown.

Fig. 4 is a further detail thereof, and Fig. 5 is a view of the release pin of said mechanism, removed. 75

In order to make clear the use and application of my invention, I will describe the general construction of the particular machine to which my invention has been applied, and with which it effects a particular combination. 80

The machine is mounted on a suitable pedestal, 1, having a flat top, 2, to which is bolted a bed plate, 3. The clamp for holding the work comprises a pair of jaws, 4 and 5, the former being a fixed jaw, and the latter a movable jaw, guided in ways 6, formed on the bed plate, and adjusted longitudinally thereof, by a feed screw 7, 90 mounted in the bearing 8, on the bed 3, and provided at its outer end with an operating crank 9. A vertically adjustable reciprocating saw frame 11, is provided at opposite ends with bearings 11', in which are 95 mounted stems 12 to which the saw blade 13 is detachably connected, being held at a slight angle to the frame back so that it gains clearance on the non-cutting stroke.

The blade 13 is strained to tension by the 100 pivoted lever 14, operated by the threaded stem 18, and having its free end disposed between a pin 17 on the stem 12, and the adjacent bearing 11' of the frame 11. The saw frame 11 is swung vertically in relation to the power shaft 28 of the machine and swings about said shaft as a pivot. The horizontally disposed pivot arm 25 carries the saw frame, and has a downwardly extending forked end 26, which forms bear- 110

ings, through which a bushing 27, about the power shaft 28 is secured. The feeding pressure may be applied to the saw frame in any suitable manner, as by the weights 35 shown in the drawings. The saw frame is reciprocated from the power shaft by suitable connections which convert the rotation of the power shaft to reciprocate the frame as shown. This connection consists of a vertical rocker arm 49, pivoted at 50 to the bed plate 3 and connected by a pitman 54 to the saw frame 11. The rotation of the power shaft 28 through the crank 45, swings the lever 49 to reciprocate 10 the saw frame 11 through the pitman connection.

In this type of machine, means are provided for relieving the saw frame of the feed pressure on the return or non-cutting stroke of the saw, without lifting the saw frame so as not to subject the teeth of the saw blade to strain and wear of contact while being withdrawn. This pressure relieving means, consists of a curved link 58, 20 pivoted to the saw guide 21. This curved link or segment works between a spring tension plunger 60, having a cylindrical head 61, and the bearing of an oppositely disposed release pin 72. The end of the plunger 60 is exposed to the link 58, and is formed as a bearing face rounded circumferentially to conform to the link 58, but flat in the direction of its width so as to provide the same bearing to the link at all 25 points across the exposed face. The spring permits an automatic take-up of any wear in the segmental link or in the face of the plunger. The plunger 60 is mounted for reciprocation in the chamber end 62 of a cam actuated lever 63, pivoted at one end at 30 64 to a casting 164 rising from the bed 3, and having a roll at its other end, disposed for alternate engagement and release by a cam 66, fast on the shaft 28. Within 35 the chamber 62, and between the rear wall thereof, and the head 61 of the plunger, is a coiled spring 67, the normal tendency of which is to maintain the head 61 in gripping contact with the link 58. Beyond the 40 rear wall the plunger stem is threaded as indicated at 68, to receive one or more check nuts 69 to hold the adjustment of the plunger. The plunger is held against rotation by a set screw 71, bearing in a channel 70.

The plunger head is normally engaged with the curved link 58 by the action of the spring 67. When the machine is started it is necessary to release this engagement in order to permit the saw to descend on the work. This release is effected manually 45 through the pin 72, rotatably mounted in a bearing 73 and having a flattened portion 74, against which a release stud 75 bears. An operating handle 77 is provided to ro-

tate the pin 72, thereby causing the flattened portion 74 to move the stud 75 against the head of the plunger 60, overcoming the spring 67 and causing the head to release the member 58. As soon as the stud 75 is released at the beginning of the cutting stroke, 50 the pressure of the spring 67 is released, and the plunger is returned to position to again grip the link 58. This gripping however, does not become effective until the cam 66 has made a half revolution, thus bringing its dwell against the cam roll of the lever 63. This moves the lever toward the link to positively grip it on the return stroke of the saw.

It will therefore be seen that the link 58 80 is alternately released and gripped on each cutting and non-cutting stroke respectively. This alternately subjects and relieves the saw to the feeding pressure of the weights 35.

In order to prevent shock on the teeth when the saw is released at the end of each return stroke, and in order to permit the saw to settle into the cut gently and without shock so that it will be "floated" as it were, 90 during its cutting action, I interpose between the pivoted arm 25 carrying the saw frame and the bed plate 3, a suitable motion checking device which in the embodiment shown, is in the form of an oil piston. As shown 95 in Fig. 3 most clearly, I provide a cylinder 108 formed at its lower end to receive a fastening 107 which connects this end of the cylinder to bed 3 of the machine. This cylinder is adapted to be filled with any 100 proper fluid such as a heavy oil, and is provided with a suitable closure at its upper end. The piston stem 110 is pivoted at its upper end at 106 to the saw frame arm 25 and passes through a cap 109 inclosing a 105 stuffing box 111 in which a packing is compressed by a cap 112 screwed on to the reduced projected end of the closure cap 109. The lower end of the stem is reduced as indicated at 113, and carries a disk 114 110 adapted to seal a plurality of openings 115 in a piston 116, slidably fitting within the casing 108, and having an extended hub 117, sleeved about the reduced end of the stem, whereby to move with said stem. Bearing against the lower edge of the hub 117, and confined between it and the head of a screw 118, set in the lower end of the stem 110, is a coil spring 119, the normal 115 tendency of which is to maintain the members 114 and 116 in sealing relation.

In my construction, the operator is relieved of the necessity of manually raising the saw frame and of holding it in a raised position while inserting new work into the 120 work clamp, thus leaving his hands free to properly adjust the work. The saw frame is raised by the weight of the operator ap-

plied to a treadle T pivoted near the base of the machine frame and operatively connected to the saw frame supporting arm 26 by a link T'. When elevated to its raised position by said treadle, the saw frame is supported by the oil piston. In the operation of the treadle, the raising of the arm 26 lifts the stem 110 from the position shown in Fig. 3, to the position shown in Fig. 2, against the pressure of the fluid as it passes through the opening 115. This pressure is sufficiently great to counteract the tendency of the spring 119, to maintain the members 114 and 116 in sealed relation, and therefore permits the separation of said members and a consequent passage of the fluid through the openings 115 from above the piston to the side below.

This action is entirely automatic and the dash pot therefore, not only permits the saw to "float" down into the cut at each rapid release of the saw by the gripping device, but also assists to check vibration, and tends to keep the saw blade steady in the kerf during the cutting action. In operation therefore, the saw frame is raised by the foot treadle T, leaving the hands of the operator free to make adjustments of the machine or the work. This raising movement is resisted slightly through the oil cylinder so that the saw rises with a smooth and steady motion. As the saw is released to make its initial contact with the work, its descent is controlled so that as it moves to the work during the rapid gripping and releasing on each reciprocation, it finally comes in contact with the work gently and steadily and without shock or jar, and without danger of breaking the teeth or of losing its alignment with the cut. Throughout its cutting operation, and at each release of the gripping mechanism, the oil piston "floats" the saw so that the resultant feed is no longer a series of sudden checks and releases, but is a merging movement in which the action is a buoyant relief sustained during each return stroke by the gripping action of the machine.

My invention may obviously be applied to various modifications of the machine shown, and may be embodied in mechanism of different sorts without departure from the spirit of my invention, if within the limits of the appended claims.

What I therefore claim and desire to secure by Letters Patent is:

1. In a cutting machine, a cutting element, means for imparting a cutting stroke thereto, gravity means for exerting feed pressure on said cutting element, and means for interrupting the feed tendency of said pressure means during the non-cutting stroke of the cutting element to permit said element to be returned to position to begin a

new cutting stroke without lifting said element from the cut previously made and in substantially the line traversed by said element on the cutting stroke, said means automatically releasing said feed pressure means when said cutting element is in position to begin a new cutting stroke, and means effective upon such release to prevent abrupt drop of said cutting element.

2. In a cutting machine, a power shaft, a cutting element reciprocated therefrom, gravity means for exerting feed pressure on said element during the cutting stroke thereof, means actuated from said power shaft and adapted to intermittently grip and release said element, thereby to alternately interrupt and release the gravity tendency of said feed pressure means, and means effective upon such release and permitting said element to settle into the cut gently and without shock under the feed tendency of the now released pressure means.

3. In a cutting machine, a power shaft, a cutting element reciprocated therefrom, gravity means for exerting feed pressure on said element during the cutting stroke thereof, and means actuated from said power shaft and adapted to intermittently grip and release said element, thereby to alternately interrupt and release the gravity tendency of said feed pressure means, and a dash pot interposed between said element and a stationary part of the machine and effective upon such release to permit said element to settle down into the cut gently and without shock under the feed tendency of the now released pressure means.

4. In a sawing machine, a frame, a saw frame pivoted thereon, gravity means for exerting feed pressure on said saw frame, automatic means for interrupting and releasing the gravity tendency of said feed pressure means, and a dash pot interposed between the pivotal connection for the saw frame and the frame of the machine and operated by the movement of said saw frame for automatically checking the feed tendency of the pressure means after release thereof to permit the saw to settle gently to the work.

5. In a cutting machine, a cutting element, means for exerting feed pressure thereon, a member to be gripped associated with said element, a gripping mechanism for alternately gripping and releasing said member according to the position of said cutting element to alternately interrupt and release the normal feed tendency of the feed pressure means, and a device operated by the position of said cutting element for sub-sidely sustaining said element when said feed pressure is released.

6. In a cutting machine, a cutting element, gravity means for exerting feed pres-

sure thereon, a member to be gripped associated with said element, a gripping mechanism for alternately gripping and releasing said member according to the position 5 for said cutting element to alternately interrupt and release the normal gravity tendency of the feed pressure means, and a device interposed between said element and a fixed part of the machine and operated by 10 the position of said cutting element for subsidingly sustaining said element when said feed pressure is released.

7. In a sawing machine, a saw, a driving mechanism therefor, means for exerting feed 15 pressure thereon, a member to be gripped, associated with said saw, a gripping device to alternately grip and release said member to interrupt and release the normal tendency of the feed pressure means according to the 20 position of the saw, a release for said member to be gripped, designed to be manually operated to initially relieve said member of the grip of said device, and means effective upon release of the feed pressure means to 25 subsidingly sustain said saw.

8. In a cutting machine, a cutting element, means for normally exerting feed pressure thereon, means for locking said cutting element to relieve it of the feed pressure, means 30 whereby said locking means is released to permit the feed, and means for subsidingly sustaining the cutting element when the feed pressure is removed from said element.

9. In a cutting machine, a cutting element, 35 means for normally exerting feed pressure thereon, means for automatically removing said feed pressure from the cutting element upon the non-cutting stroke, and for return-

ing the cutting element to position to begin a new cutting stroke without lifting from 40 the cut and in substantially the line traversed by said element on the cutting stroke, and means for subsidingly sustaining said element when relieved of the feed pressure.

10. In a machine saw, a reciprocable saw, 45 means for normally exerting feed pressure thereon, means for automatically removing the feed pressure from the saw upon the non-cutting stroke and operating to allow the saw to be returned to position to begin 50 a new cutting stroke without lifting from the saw cut and in substantially the line traversed on the cutting stroke, means for raising the saw frame to permit the work to be changed, and means for subsidingly 55 sustaining the saw in raised position.

11. In a machine saw, a reciprocable saw, means for normally exerting feed pressure thereon, saw-locking means for automatically removing the feed pressure from the 60 saw upon the non-cutting stroke and operating to allow the saw to be returned to position to begin a new cutting stroke without lifting from the saw cut and in substantially the line traversed on the cutting 65 stroke, means for raising the saw frame to permit the work to be changed, and a fluid-operated device for subsidingly sustaining the saw in raised position.

In testimony whereof I affix my signature 70 in presence of two witnesses.

LAROY S. STARRETT.
